C. LUNDQUIST

WIRELESS SYSTEM

Filed July 25, 1922

FIG. 1.

Inventor
CLIFFORD LUNDQUIST.

By Richard Oliver,
Attorney.

UNITED STATES PATENT OFFICE.

CLIFFORD LUNDQUIST, OF WINFIELD, IOWA.

WIRELESS SYSTEM.

Application filed July 25, 1922. Serial No. 577,386.

To all whom it may concern:

Be it known that I, CLIFFORD LUNDQUIST, a citizen of the United States, residing at Winfield, in the county of Henry and State 5 of Iowa, have invented certain new and useful Improvements in Wireless Systems, of which the following is a specification.

This invention relates to wireless transmission of intelligence and has special reference to apparatuses for transmitting 10 telegraphic signals on wireless telephone circuits.

The principal object of the invention is to provide an improved and simple arrangement of apparatus for the purpose set forth.

A second important object of the invention is to provide an improved form of telephonic transmitter for use in connection with the sending of wireless telegraphic 20 signals.

A third important object of the invention is to provide novel means for damping the vibrations of the diaphragm in such a telephonic transmitter.

With the above and other objects in view, the invention consists in general of certain novel details of construction and combinations of parts hereinafter fully described, illustrated in the accompanying drawings, 30 and specifically claimed.

In the accompanying drawings, like characters of reference indicate like parts in the several views, and:—

Figure 1 is a diagrammatical view of the 35 "hook up" for the apparatus in a simple and typical form.

Figure 2 is a transverse section through the telephonic transmitter used herewith and showing the damping means.

Figure 3 is a front view of said transmitter with a portion of the casing broken away to show the damping means.

In carrying out the objects of the invention a simple form of "hook up" has been disclosed which embodies the primary circuit A, secondary circuit B and aerial circuit C. The circuits B and C are of the ordinary form and will not be described in detail except to say that circuit B receives its current impulses from the circuit A through a modulation transformer or electric modulator 10. In the primary circuit there is provided a source of power 11 which is here in-

dicated as a direct current generator, although any other suitable source of power 55 may be utilized. In series with the source 11 is a receiver 12 the construction of which will be hereinafter set forth, a transmitter 13 and a telegraphic key 14. Also connected in series with the source 11 is a motor driven interrupter 15 and a variable resistance 16. The line through the interrupter and resistance is connected to one pole of the primary of the transformer 10, the other line being connected to the other pole of said 60 transformer primary. With this circuit it will be noted that the interrupter is driven at a very high rate of speed so that the interruptions pass beyond the audible range 65 and it is to this end that a direct current and interrupter are preferred to the usual alternating current generator. This arrangement produces a harmonic sound of greater intensity and the tone can be changed by varying the resistance 16 or by 70 utilizing the peculiar construction of the receiver 12.

This receiver 12 comprises the usual casing 17 wherein are electromagnets 18 having an armature in the form of a diaphragm 19. Secured to one side of the casing is a bracket 20 carrying on its extremity a nut 21 wherethrough passes an adjusting screw 22 having swivelled connection to a dampener 23 of felt, rubber, or the like and 80 which rests against the diaphragm 19. The position of this dampener may be shifted radially of the diaphragm by turning the screw 22 as shown in Figure 2. Whenever the dampener is moved toward the center of 85 the diaphragm a greater effect will be obtained than when it is moved toward the periphery of said diaphragm and in this manner the vibration of the diaphragm can be controlled.

There has thus been provided a simple and efficient device of the kind described and for the purposes specified.

It is obvious that minor changes may be made in the form and construction of the 100 invention without departing from the material principles thereof. It is not therefore desired to confine the invention to the exact form herein shown and described, but it is wished to include all such as properly come 105 within the scope claimed.

Having thus described the invention what is claimed as new, is:—

In a receiver of the class described, a casing a diaphragm forming an armature, a bracket carried by said casing and provided with a nut on its extremity, a screw extending through said nut, and a damper swivelled to said screw and transversing said diaphragm, said bracket and screw being

arranged to move the damper radially of the diaphragm.

In testimony whereof I affix my signature in presence of two witnesses.

CLIFFORD LUNDQUIST.
